CLAIM

The ornamental design for a tracking device holder, as shown and described.

DESCRIPTION

FIG. 1 is a perspective view of a design for a tracking device holder;

FIG. 2 is a side view thereof;

FIG. 3 is another side view thereof;

FIG. 4 is a front view thereof;

FIG. 5 is a back view thereof;

FIG. 6 is a top plan view thereof;

FIG. 7 is a bottom plan view thereof;

FIG. 8 is a perspective view of the tracking device holder in use; and,

FIG. 9 is an exploded view thereof.

The broken lines illustrate portions of the tracking device holder that form no part of the claimed design.
